CLAIM

The ornamental design for a finger mounted squeegee
for sport goggles, as shown and described.

DESCRIPTION

FIG. 1 is a perspective view of a finger mounted squeegee
for sport goggles, showing my new design;
FIG. 2 is a top plan view thereof;
FIG. 3 is an end elevational view thereof, with the
retaining strap secured; and,
FIG. 4 is a side elevational view thereof.

FIG. 1

FIG. 2

FIG. 3

FIG. 4
